(57) **CLAIM**

An ornamental design for a shock absorbing head cap, as shown and described.

DESCRIPTION

FIG. 1 is a front perspective view of a shock absorbing head cap showing my new design;

FIG. 2 is a side view thereof, the opposite side being a mirror image;

FIG. 3 is a front view thereof; and,

FIG. 4 is a rear view thereof.

The crosshatch surface shading is understood to repeat throughout the indicated area. The broken lines on the cap represent conventional stitching. The person shown in broken lines forms no part of the claimed design.
